UNITED STATES PATENT OFFICE.

ABNER B. MAGOUN, OF BRANT ROCK, MASSACHUSETTS.

SELF-FASTENING POSTAL CARD.

No. 853,889.

Specification of Letters Patent.

Patented May 14, 1907.

Application filed August 10, 1906. Serial No. 329,992.

To all whom it may concern:

Be it known that I, ABNER B. MAGOUN, a citizen of the United States, residing at Brant Rock, in the county of Plymouth and State of Massachusetts, have invented new and useful Improvements in Self-Fastening Postal Cards, of which the following is a specification.

The object of this invention is to provide a correspondence or postal card which can be so folded as to conceal and protect the written matter thereon and also fastened so that it will not unfold.

The object of the invention is further to provide a correspondence or postal card which, after being fastened, as set forth, may be sealed by attaching a stamp thereto.

The invention consists in a correspondence or postal card constructed as hereinafter described and particularly as set forth in the claims.

Referring to the drawings: Figure 1 is a plan view of my improved postal card showing the same unfolded, as viewed from the inner face thereof. Fig. 2 is a plan view of the same folded. Fig. 3 is a plan view of a postal card constructed in accordance with my invention with three folds. Fig. 4 is a modified form of my invention in which two tongues are employed instead of one as in the forms illustrated in Figs. 1, 2 and 3.

Like numerals refer to like parts throughout the several views of the drawings.

In the drawings, Figs. 1 and 2, 5 is a sheet 35 of paper or card-board folded transversely thereof along the lines 6 and 7 to form a front 9, a back 8, and a flap 10. The flap 10 has a tongue 11 which projects from one end of the sheet 5 and is adapted, when the sheet is folded as illustrated in Fig. 2, to project into a slit 12 formed in the back 8 and thus lock said back and flap against unfolding. The side 13 of the tongue 11 extends at an angle from the body portion of the flap toward the side 14 of the sheet 5 adjacent thereto, while the side 15 of said tongue preferably extends at an angle away from the side 16 of said sheet.

In using my improved postal card writing 50 may be placed upon the inner face of the back 8 and of the front 9. The back 8 is then folded over against the front 9 and the tongue 11 slipped through the slit 12 in said back, thus folding and locking the same against unfastening. A stamp 17 may be

placed upon the back after the card has been folded, as illustrated in Fig. 2, thus sealing the flap to the back, or the stamp may be printed upon the front 9 as in the ordinary postal card.

It will be seen that my improved postal card is particularly adapted for souvenir postal cards in which the picture can be printed upon the inner face of the front 9 and the writing on the inner face of the back 8 and then when the postal is folded the writing and the picture will be protected from injury in the mails.

Fig. 3 illustrates a postal card like that illustrated in Figs. 1 and 2, except that an intermediate part 18, folded along the line 19, is added thereto. In all other respects this form of my invention is the same as that illustrated in Figs. 1 and 2, and, in folding, the intermediate sheet 18 is first folded in 75 against the back 8 and then said back and intermediate sheet are folded against the inner face of the front 9, the tongue 11 being then inserted in the slit 12, as in the form illustrated in Figs. 1 and 2.

In Fig. 4 another modified form of my invention is illustrated in which 5' is a sheet of paper creased to fold along the lines 6' and 7' having a front 9', a back 8', and a flap 10'. This particular form of my invention has a 85 flap provided with two tongues 11' and 11'', the tongue 11' being adapted to enter a slit 12' and the tongue 11'' to enter a slit 12'' in the back 8'. The sides 13' and 15' of the tongue 11' extend at an angle toward the 90 side 14' of said sheet adjacent thereto and the sides 13'' and 15'' of the tongue 11'' converge toward each other, the object of this construction being to allow the tongue 11'' to be withdrawn first in unfolding the card, thus 95 allowing the flap to be bent upwardly at the right hand side to a slight extent and the tongue 11' to be thus withdrawn from the slit 12'.

It will be seen that in addition to writing 100 upon the inner face of the back 8 and front 9, the outer face of the back 8 may also be written upon, if desired, as in the ordinary postal card. The card may be used in the manner of the ordinary postal card with 105 printing and a Government stamp on the front face thereof and also the address of the party to whom it is sent written thereon, or the address may be written upon the front of said postal card, writing placed upon the 110

outside of the back as well as the inside thereof, and stamp 17 used to seal the card and prevent its unfolding.

It will be noticed that the slit 12 is made in the back 8 at one side of the longitudinal median plane thereof, so that when the card is folded as illustrated in Fig. 2 the tongue enters the slit 12 above the longitudinal median plane of said card and this location of the slit 12 is very important in the device of my invention, for the reason that when located substantially as shown, if the card is bent longitudinally thereof, either toward the back or toward the front, the flap will not slip out of the slit, experiment having shown that if the slit 12 is placed lower than shown in Fig. 2 or nearer the center of the flap the tongue will slip out of the slit 12 much more readily when the card is bent than when said slit is located as shown.

If desired, adhesive material may be placed upon the tongue 11 upon the outer face thereof—that is, upon the opposite face of said tongue to that which is seen in Fig. 1, and when the postal card is folded as in Fig. 2 the adhesive material may be moistened, prior to slipping the tongue through the slit 12, and subsequently the tongue with its adhesive material thereon, may be pressed against the inner face of the back 8, thus sealing the card and preventing the tongue from being withdrawn from the slit. To open the card under these conditions it will be necessary to cut the tongue 11 away from the flap 10.

Having thus described my invention, what I claim and desire by Letters Patent to secure is:

1. A postal card comprising a sheet of paper folded to form a front, a back having a slit therein, and a flap, said flap having a tongue

extending longitudinally from and beyond one end of said sheet, one side of said tongue extending at an angle toward the side of said sheet adjacent thereto and parallel to the opposite side of said tongue, whereby said tongue is adapted to project into said slit and lock said card against unfolding.

2. A postal card comprising a sheet of paper folded to form a front, a back having a slit therein, and a flap, said flap having a tongue extending longitudinally from one end of said sheet, one side of said tongue extending at an angle toward the side of said sheet adjacent thereto, the opposite side of said tongue extending at an angle away from the side of said sheet adjacent thereto, said sides of said tongue substantially parallel to each other, whereby said tongue is adapted to project into said slit and lock said card against unfolding.

3. A postal card comprising a sheet of paper folded to form a front, a back having slits therein, and a flap, said flap having a plurality of tongues extending longitudinally from one end of said sheet and adapted to project into said slits and lock said card against unfolding, one side of one of said tongues extending at an angle toward the side of said sheet adjacent thereto, the opposite sides of said tongue being substantially parallel to each other, the opposite sides of the other of said tongues converging toward each other.

In testimony whereof I have hereunto set my hand in presence of two subscribing witnesses.

ABNER B. MAGOUN.
